FARE BOX

Samuel J. Bell, Springfield, Mass., assignor, by
mesne assignments, to Ohmer Fare Register
Company, Dayton, Ohio, a corporation of New
York

Application March 26, 1929, Serial No. 349,922
Renewed April 14, 1933

16 Claims. (Cl. 232—15)

My invention relates generally to improvements in fare boxes of the type of that which forms the subject of United States Letters Patent No. 1,499,904, dated July 1, 1924, and specifically to improvements in the box of said patent; and the primary object of said invention is further to increase the safety of a box of this character and its capability of guarding or protecting the contents of the same from the time any coin, token, or ticket is deposited therein by the purchaser until it is removed therefrom by a duly authorized official, to the end that theft between such periods is practically impossible.

As factors in accomplishing the above-named object mention is made of a four-point, semi-automatic lock which must be worked through before the cash drawer, once properly inserted in the case, can be removed, and whereby the shutter for the cover of said drawer is closed and locked before such removal is possible, checks in case of mutilation of or improper interference with certain parts for the purpose of surreptitiously gaining access to the cash drawer and unlawfully abstracting the contents therefrom, and visual checks readily observable by an inspector.

A further object is to effect the ringing of the bell associated with the register only after said register has been operated to record the fare each time, and thus render it impossible to manipulate the register in a manner to prevent recording while at the same time sounding the bell.

Another object is to provide the box with baffle plates of a character that practically precludes removal of a coin, token, or ticket with the aid of a piece of string or wire.

Other objects and advantages will appear in the course of the following description.

A preferred embodiment of the invention, whereby I attain the objects and secure the advantages of the same, is illustrated in the accompanying drawings, and I will proceed to describe said invention with reference to said drawings, although it is to be understood that the form, construction, arrangement, etc., of the parts in various aspects may be varied or modified without departing from the spirit of the invention, or exceeding the scope of what is claimed.

In the drawings, in which like numerals designate like parts throughout the several views, Figure 1 is a side elevation, with parts broken away and in section to disclose interior construction, and a portion broken out to shorten the view, of a fare box which embodies a practical form of my

invention as aforesaid; Fig. 2, a rear elevation of the upper portion of the receiving hopper and of the register plate and register; Fig. 3, a front elevation, with parts broken away and in section, to disclose interior construction, and a portion broken out as in the first view, of said box; Fig. 4, an end elevation of the tell-tale replacer; Fig. 5, a side elevation of said replacer, an intermediate portion being broken out; Fig. 6, a vertical section through the box taken on lines 6—6, looking in the direction of the associated arrow, in Fig. 3; Fig. 7, a section through the upper portion of the box on lines 7—7, looking in the direction of the associated arrow, in Fig. 6; Fig. 8, a vertical section taken on lines 8—8, looking in the direction of the associated arrow, in Fig. 7; Fig. 9, a horizontal section through the observatory, taken on lines 9—9, in Fig. 6; Fig. 10, a sectional detail showing the shutter-holding arm in operative position; Fig. 11, a detail of the parts and members appearing in the preceding view, but taken at right-angles thereto; Fig. 12, a bottom plan of a portion of the drawer cover, shutter, and latch mechanism, showing said shutter fully closed and locked; Fig. 13, a similar view showing the shutter partially closed and locked; Fig. 14, a detail of said latch mechanism with the bolt set; Fig. 15, a bottom plan of said cover, shutter, and latch mechanism, the shutter being shown at the forward end of its travel, with the latch bolt released from its detent; Fig. 16, a front elevation of the case and drawer locking mechanisms, the front sides of the case and drawer being cut away and said mechanisms being normally disposed; Fig. 17, an operative detail of said last-named mechanisms; Fig. 18, a sectional detail of the discharge hopper and inspection plates, and, Fig. 19, a rear elevation of the drawer key-operated lock.

The casing of this fare box comprises a case 1 in the front of which is a large opening to receive a cash drawer 2, and in the top of which is a large opening represented at 3 in Fig. 6, and a small opening or slot represented at 4 in Figs. 16 and 17, the slot being in front of the second-named opening; an observatory 5 mounted on a base 10 that in turn is mounted directly on the top of said case, said observatory being open at the top and bottom and said base being open in the center; and a receiving hopper 11 mounted on said observatory.

At the bottom of the case 1 are two tracks 12 extending longitudinally or between the front and back of said case. The tracks 12 are adapted to receive thereon the bottom of the drawer 2,

and said bottom is provided with two ribs 13 to engage said tracks on the inner sides thereof and guide said drawer in a straight course. To facilitate the introduction of the drawer 2 into the case 1 and onto the tracks 12, each of the latter at its forward terminal on top is inclined downwardly and forwardly, as shown at 14 in Figs. 1 and 6. The bottom of the case 1 between the tracks 12 may be open.

10 The observatory 5 is made up of glass plates and metallic corner-pieces located between the base 10 and an exterior flange 15 at the upper end of a baffle hopper 16 which extends down into said observatory. The receiving hopper 11 has a flanged base 17 which is received on the flange 15. Four bolts 18 and the same number of nuts 19 and washers 20 are employed to fasten together securely the hoppers 11 and 16 and the base 10, with the glass plates and corner-pieces between. 15 Each bolt 18 passes down through the base 17, the flange 15, the observatory 5, the base 10, and the top of the case 1, also through an exterior lug on a discharge hopper 21 located in said case below the opening 3, to receive one of the washers 20 and one of the nuts 19 thereon under said lug. 20 A tube 22, of yielding material, through which each bolt 18 also passes, separates the glass from the bolt, and cushions 23-23 at the top and bottom of the glass prevent the same from coming 25 into contact with the flange 15 above and the base 10 below—see Fig. 3.

The base 10 has sloping front and back pieces 24-24 and sloping side pieces 25-25 which extend downwardly into the case opening 3 onto the upper edge of the discharge hopper 21. The base pieces 24 project slightly beyond the front and back edges at the top of the hopper 21, while the base pieces 25 at their inner edges are flush with the side edges at the top of said hopper.

40 The drawer 2 is provided with a cover 26 in the top of which is an opening 27 located directly beneath the opening in the bottom of the discharge hopper 21, when said drawer is in place in the case 1, and of the same size and shape as said last-named opening. There is just sufficient space between the tops of the tracks 12 and the bottom of the hopper 21 to admit the drawer 2. The inclined pieces 24 and 25 of the base 10 form a short funnel leading from the interior of the observatory 5 to the interior of the hopper 21. The cover 26 is provided with a shutter 28 in which is an opening 29 of the same size and shape as the cover opening 27 and can be located directly under the same, when there 45 is a continuous passage from the open mouth at the top of the receiving hopper 11 to the interior of the drawer 2, such passage leading through said hopper, the baffle hopper 16, the observatory 5, the base 10, the discharge hopper 21, the cover 26, and the shutter 28.

60 Normally the top of the hopper 21 is closed by means of two inspection plates 30. These plates are secured adjacent to their outer (when horizontally disposed) longitudinal edges to two horizontal rock shafts 31 and 32 journaled in the front and back sides of the hopper 21 near the top. The plates 30, when horizontally and normally disposed, meet at their free longitudinal edges, and bear against the parts of the bottom 65 edges of the pieces 24 that project inwardly over the open upper end of the hopper 21, which edges limit the upward movement of said plates. At this time the aforesaid passage through the casing is closed.

70 75 The objects dropped into the hopper 11 find

their way quickly to the plates 30 where they can be inspected before being dumped into the hopper 21. The mechanism for holding and operating the plates 30 will next be described.

80 Mounted on and rigidly secured to the shaft 31 at the forward terminal is an operating lever 33 which extends upwardly through the slot 4 in the case 1, and mounted on and secured to the shaft 32 at the forward terminal is a rocker arm 34. A lever 35 is pivotally connected at 36 with a depending lug 37 in the case 1. A link 38 has its forward terminal pivotally connected at 39 with the lever 33, and the other terminal pivotally connected at 40 with the lower or forward (according to position) terminal of the lever 35, and a link 41 has its forward terminal pivotally connected at 42 with the upper or rear (according to position) terminal of said first-named lever, and the other terminal pivotally connected at 43 with the free terminal of the arm 34. A spring 44 extends between the pivot 43 and a pin 45 on the link 38, and tends constantly to rock the shaft 31 to the right and the shaft 32 to the left, through the medium of the links 38 and 41 and the lever 35, and owing 90 to the location of the pivot 39 on the lever 33, and thus normally to retain the inspection plates 30 up under and in contact with the base pieces 24, as clearly shown in Fig. 16.

95 Upon rocking the lever 33 to the left, against the resiliency of the spring 44, the shafts 31 and 32 are rocked in the directions to swing the plates 30 down into a vertical position, as indicated by broken lines in Figs. 17 and 18, said lever acting directly on said first-named shaft and indirectly 100 or through the intervening parts and members on said second-named shaft. In this manner the object or objects, if any, on the plates 30 are dumped into the hopper 21. Upon the release of the lever 33 the spring 44 immediately contracts and brings about an action of the parts and members then controlled by said spring, including the plates 30, whereby the latter are closed.

110 The lever 33 has a disc-like hub, as will have been observed, and in such hub is an indentation or notch 46. This notched hub is a part of the locking and releasing mechanism for the drawer 2 including the cover 26 and the shutter 28.

115 The drawer 2 has an exterior handle 47 at the front end, also a key lock 48, and is equipped at the back end with another key lock 49.

120 Referring to Fig. 19, wherein a rear elevation of the lock 48 appears, it will be seen that a link 50 has one terminal pivotally connected at 125 51 with an eccentrically arranged member 52 of said lock, and the other terminal pivotally connected at 53 with a horizontal bolt 54 which slides in a passage through a projection 55 integral with the drawer 2. The projection 55 extends inwardly from the left hand side of the drawer 2, and the passage therethrough opens at the inner end adjacent to the lock 48 and at the outer end through said side. Thus the bolt 54 can be projected with its outer terminal behind the left-hand vertical flange (56) which bounds the drawer opening in the front of the case 1 on that side.

130 140 145 When the lock 48 is operated by its key (not shown) in one direction, the bolt 54 is advanced by the lock member 52, through the medium of the link 50, until the free terminal of said bolt is behind the flange 55, and, when said lock is operated in the opposite direction, said bolt, through the same medium as before, is retracted.

When the drawer 2 is pushed into the case 1 as far as possible, and the bolt 54 advanced, the latter locks said drawer securely in place in said case, but, upon retracting said bolt, said 5 drawer is left free to be withdrawn from said case, so far as the lock 48 is concerned.

The lock 49 is equipped with oppositely disposed, horizontal bolts 56—56, of the spring-pressed type. These bolts are located inside of 10 the drawer 2 a short distance from the back side and a short distance from the top of said drawer. At the forward end of the cover 26 are two lugs 57 that are receivable in two openings 58 in the front of the drawer 2 near the top thereof. The 15 lugs 57 when in place are discernible through the openings 58 in which they are then located, and so afford visual evidence from the outside that the cover 26 is in place on the drawer and in the upper part of the same. Thus the lugs 57 20 serve the purpose of securing the cover 26 at the front end, and as a means of disclosing the presence of said cover to any observer. Adjacent to the rear end of the cover 26, underneath, are two depending, hooked lugs 59 in position to 25 snap into engagement with the lock bolts 56, when said end of said cover is forced downwardly. The lock lugs 59 depend from a transverse bar 60 that has its ends secured by screws or other means to two lugs 61 on the bottom of the 30 cover 26, which lugs are received in the rear corners of the drawer 2 when said cover is in place.

In applying the cover 26 to the drawer 2, the lugs 57 are first inserted in the openings 58, said 25 cover being tilted to permit this to be done, and then the cover is laid down on the top of said drawer, with the lugs 61 in the back corners, sufficient force being employed to snap the locking lugs 59 into engagement with the bolts 56, 40 unless said bolts be in retracted position at the time, in which latter event they are advanced with the aid of the key (not shown) to engage said locking lugs. The cover is now held immovably on the drawer, with parts extending 45 down inside of said drawer, and can not be removed until the lock 49 is operated to withdraw the bolts 56 from engagement with the lugs 59, when the rear end of the cover can be lifted out and off of the drawer, and the cover moved 50 to withdraw the lugs 57 from the front end of said drawer.

The lugs 61, lugs 62 and 63 at the front end from which the lugs 57 project, parallel flanges 64 having at their inner ends lugs 65 and 66 respectively, and an extension flange 67, all on the under side of the cover 26, form guides between which the shutter 28 slides. The shutter 28 slides on the bar 60 and straps 68 and 69. The strap 68 is secured by screws or other means to the 65 lugs 62 and 65, and the strap 69 is secured by screws or other means to the lugs 63 and 66. Let into and fastened to the flange 67 is a bar 70 having a notch 71 in and five (more or less) ratchet teeth 72 on the inner longitudinal edge thereof. The bar 70 is on the right-hand side of the cover 26. The strap 69 has a forward knock-off lug 73 and a rear stop 74.

On the top of the cover 26 are two longitudinally extending ribs 75 having flaring inner sides to embrace the sides of the lower part of the hopper 21, and a transverse rib 76 having an inner flaring side to bear against said part of said hopper in front, when the drawer 2 is in place, thus with the hopper cutting off access 75 from the outside to the cover opening 27 and

the shutter 28. There may also be another guard rib 77 in front of the rib 76. The right-hand rib 75 may be continued forward to meet the rib 77.

Mounted on and secured by screws or other means to the top of the cover 26, at the right of the guard ribs is a lock-stop block 78. This block might be integral with the cover, but it is preferred to make the same separate therefrom and secure it thereto with double sets of screws or by other means, because said block should be of such hard metal as to render it difficult to cut or otherwise remove a portion thereof. Further explanation in regard to this matter will subsequently be given.

The shutter 28 is substantially the same length as the cover 26, but has a lip 79 at the rear end which extends upwardly behind said cover. In front of the lip 79 is a slot 80 in the cross-piece at the rear end of the shutter 28. When the drawer 2 is moved back in the case 1, the rear end of the shutter 28, at opposite points adjacent to the ends of the slot 80, encounters two bosses 81 on the back side of said case, and bear on said bosses until said drawer is removed from the case. An opening 82 in the back part of the shutter 28 100 is made to convert such part into a handle for convenience in carrying the drawer with the cover and shutter. A hole 83 is made in the shutter cross-piece, which is between the openings 29 and 32, to receive a pin 84. The object 105 of this pin will presently be explained. A spring 85 extends from a horizontal pin 86 projecting from the right-hand end of the cross bar 60 to a pin 87 projecting from the left-hand side of the shutter 28. The spring 85 is of sufficient 110 strength only to maintain the shutter against its own weight in advanced position, or rearwardly disposed to the full extent, with the back portion out of the cover. In the absence of the spring 85, the shutter, when unlatched and in an 115 upright position, would drop down in the cover and trip the latch mechanism next to be described, as will presently appear.

Within the shutter 28, adjacent to the forward end and opening through the right-hand 120 side thereof, is a horizontal passage 88 for a latch bolt 89. A spring 90 is located in the passage 88, between the inner end of said passage and the inner end of the bolt 89, and tends to force the latter downwardly into contact with 125 the bar 70 and engagement with the teeth 72 or the recessed part at 71. There is a longitudinal slot 91 in the bottom of the passage 88 under the bolt 89, and a pin 92 extends downwardly from said bolt through said slot. The pin 92 130 is provided with a cover plate 93 for the bottom of the slot 91. A detent 94 for the bolt 89, has its inner end pivotally connected at 95 with the bottom of the shutter 28, and is provided in the front edge with a notch 96 to receive the pin 92 135 when said bolt is retracted against the resiliency of the spring 90. The knock-off lug 73 is in the path of the outer terminal of the detent 95. A pin 97 depends from the bottom of the shutter behind the outer-terminal portion of the detent 140 95, and the stop 74 is in the path of said pin.

The back side of the drawer 2 is cut down on the top in the center, as represented at 98, to accommodate the rear-end portion of the shutter 28.

The bolt 89 is set by grasping the pin 92 and retracting said bolt, against the resiliency of the spring 90, and swinging the detent 94 on its pivot 95 into engagement with said pin with the latter in the notch 96—see Fig. 14. When the 150

detent 94 is swung out of engagement with the pin 92, the bolt 89 is released to its spring and by the latter forced outwardly against the bar 70.

Before placing the cover 26 on and in the top 5 of the drawer 2, with the lugs 57 in the openings 58 and the rear-end portion of the shutter 28 in the recess 98, the latch bolt 89 is set, and the spring 85 positions said shutter with the pin 97 against the stop 74, although that is merely incidental, the principal object of said spring having hereinbefore been set forth—see Figs. 14 and 17. Now, if the shutter 28 be secured by means of the lock 49, the drawer 2 with its parts and members is ready to be placed in the case 1. 10 When the drawer is shoved into the case, the shutter is moved forward until the detent 94 encounters the lug 73 and thereby caused to release the bolt 89 to its spring, and the opening 29 is exactly under the opening 27, as illustrated in 15 Figs. 6 and 15. Upon the withdrawal of the drawer from the case, the shutter is held (by means yet to be described) while said drawer is moving, and the bar 70 slides forward with the drawer until the pin 97 contacts with the stop 25 74, and by which time the outer end of the bolt 89 enters the notch 71, having clicked over the teeth 72, when the opening 27 is completely closed by the shutter, as shown in Fig. 12. The bolt now prevents the shutter from being opened. 30 In the event the shutter 28 be prevented from completely closing the opening 27, as by the presence in said opening of some object surreptitiously or improperly introduced, the bolt 89 engages one of the teeth 72 and so prevents inward movement of the shutter to uncover more of said opening, in which connection attention is called to 35 Fig. 13. Without the teeth 72 the presence of an object, such as a strap, in the openings 27 and 29 would prevent the shutter from closing fully and the bolt 89 from entering the notch 71, consequently said shutter could be opened wide as the drawer was removed from the case. With the shutter locked in partially closed position when delivered at the office, it is immediately evident that someone has tampered with the 40 parts.

The drawer 2, when closed and locked, is handled by means of the protruding portion of the shutter 28, in fact said drawer is handled by the same means before as well as after it is placed in the case 1. Owing to the somewhat rough usage the drawer receives after being taken out of the case, the bolt 89 is subjected to great strain, a strain that sometimes breaks the bolt, and to 45 prevent this I provide the pin 84. As soon as the conductor or other authorized person removes the drawer from the case, he slips the pin 84 through the hole 83 now located directly back of the rear edge of the cover 26, and said pin and edge take any blows and the strain off of the bolt 89. The pin 84 may also be used after the latch mechanism has been set, in order to prevent the shutter from being moved, against the resiliency of the spring 85, into the cover. But in any event 50 the pin 84 must be withdrawn before the drawer can be inserted in the case.

The latch mechanism constitutes part of the four-point lock which controls the removal of the drawer 2 from the case 1, and causes the shutter 28 to assume its closed and locked position. The other elements of the four-point lock 55 will next be described.

Journalized in suitable bearings in the case 1, at the right-hand side thereof, is a horizontal rock shaft 99. This shaft projects beyond the front

side of the case, and has mounted on and secured to such protruding terminal an operating lever 100, which extends upwardly and to the left from said shaft. Mounted on and secured to the shaft 99 inside of the front of the case is a drawer-lock 80 arm 101, also a stop and lock arm 102, the latter being part of the former and in the same vertical plane with the operating lever 33. Mounted on and secured to the shaft 99 at the rear terminal is a shutter-lock arm 103. A spring 104 has one end secured to the shaft 99, is wound around said shaft, and at the other end bears against the right-hand side of the case 1. The spring 104 is thus arranged to rock the shaft 99 to the right. 85

The arm 101 extends downwardly from the shaft 99, and a horizontal stop pin 105 is set in the front of the case 1 in the path of said arm to limit the movement of the same and of the connected parts and members in the directions imparted thereto by the spring 104. Normally 90 the arm 101 is retained by the spring 104 in contact with the pin 105. When the lever 100 is swung downwardly it actuates the shaft 99 in the direction to swing the arm 101 to the right and into contact with the adjacent side of the case 1, 95 and movement in this direction is limited by said side.

The arm 102 extends upwardly from the shaft 99, and the unnotched periphery of the hub of the lever 33 is normally in the path of said arm 105 and prevents movement to the left of said shaft, but, when said lever is rocked, against the resiliency of the spring 44, to the left to open fully the inspection plates 30, the notch 46 is brought into position to receive the outer terminal of the 110 arm and thus enable said shaft to be rocked, against the resiliency of the spring 104, in the direction to swing the arm 101 downwardly—see Fig. 17. Then the arm 101 is out of the path of the block 78. At all other times the arm 101 115 is in the path of the block 78, it being assumed in this and the other condition that the drawer 2 is in the case 1. First the lever 33 must be rocked and then the lever 100. Upon releasing these two levers their controlling springs respectively return them and the connected parts and members to former and initial or normal position. While the arm 102 is in the notch 46 the lever 33 is held thereby and the inspection plates 120 prevented from closing. With the arm 102 in normal position the lever 33 can be and is operated from time to time to open and close the inspection plates, and when so operated does not affect or act on any other mechanism. 125

While the arm 101 is in contact with the pin 130 105 the arm 103 is in an approximately horizontal position, and extends to the left from the shaft 99 over the slot 80 in the shutter 28 when the latter is in place. When, however, the parts are actuated against the force of the spring 104, the arm 103 is swung down into the slot 80 behind the lip 79, as clearly shown in Figs. 10 and 11, and so prevents the shutter 28 from being drawn forward with the drawer 2 until released by said arm. The arm 103 is swung up again to release 140 the shutter upon the reverse movement of the shaft 99.

While the arm 102 is in the notch 46 the inspection plates 30 are held open, as hereinbefore stated, consequently the shutter 28 can not be 145 moved to close the opening into the drawer 2 before whatever is on said plates is dumped into said drawer.

In inserting the drawer 2, after setting the latch mechanism, the inner end of the block 78 150

encounters the arm 101 and makes it necessary to rock the lever 33 and then the lever 100, both to the left, in order to remove said arm from the path of said block. The lever 100 should not be operated until the drawer is far enough within the case to locate the lip 79 back of the arm 103 when the latter is swung down after said lever is swung up. The drawer can now be pushed into the case to the full extent, the lever 100 and the lever 33 meanwhile being released. Upon the release of the lever 100 the arm 101 takes position in front of the block 78 and so prevents the drawer from being drawn outwardly. The drawer is finally secured with the key lock 48.

15 The four-point lock consists of the lever 33, the arms 101, 102, and 103, with the latch mechanism, and the associated and connected parts and members.

16 To withdraw the drawer 2 with the shutter 28 closed and locked, after releasing said drawer from the key lock 48, the operation is as follows:

17 The lever 33 is thrown into position to release the arm 102 by reason of the new position of the notch 46, the lever 100 is pressed downwardly to withdraw the arm 101 from in front of the block 78, and to locate the free terminal of the arm 103 in front of the lip 79, the drawer is drawn outwardly, said block then passing and moving under said second-named arm, and thereby retaining 30 said third-named arm down in front of said lip, until the block passes forward clear of the associated part. Then the arm 103 releases the shutter, but not before the drawer cover 26 moves forward a sufficient distance to close and secure 35 with the latch mechanism said shutter, the bolt 89 being tripped by the time the drawer reaches its innermost position in the case.

18 The pin 84 may now be inserted in the hole 82 and the drawer carried to the office where the 40 cover 26 is released by the lock 49 and taken from said drawer and the latch mechanism of the bolt 89 reset, the drawer is emptied, and said cover is returned to place, and locked, when the drawer is again ready to be returned to the case.

19 Without operating the lever 33 the arm 101 can not be withdrawn from in front of the block 78, said arm can not be so withdrawn without operating the arm 103, and the latch mechanism is certain to be operated by the withdrawal of the 50 drawer because of the engagement between the arm 103 and the lip 79. Meanwhile the arm 102 is holding the lever 33 against the action of its spring, and the inspection plates 30 are thereby prevented from closing. As soon as the lever 33 is released from the arm 102, the inspection plates are closed.

20 Should the latch mechanism be left without setting the lever 103 would cause said mechanism to be operated to securely fasten the shutter 28 in closed position, upon the removal of the drawer. In the event the shutter were tied or otherwise fastened in open position, the arm 103 would prevent full introduction of the drawer into the case. If the rear end of the cover 26 were blocked to 65 prevent the same from closing down tightly on the drawer top and being secured with the lock 49, the elevated end of said cover would encounter the hopper 21, upon inserting the drawer in the case, and further inward movement be prevented. Knocking off the lip 79, to destroy the effect of 70 the latch mechanism, would produce a quickly noticeable condition; so, also, would cutting off the inner end portion of the block 78, for the purpose of enabling the shutter to be released from the arm 103 before the latch mechanism operates.

25 But in the latter case dependence need not be placed solely on the eye or a measuring instrument, because the teeth 72 serve to lock the shutter before the bolt 89 reaches the notch 71, and would do so if said block were cut off in the manner just mentioned so that the arm 101 becomes sooner released and the arm 103 too soon releases the shutter.

30 To prevent "fishing" objects out of the observatory 5 with wire or string I provide upper and under baffle plates 106 and 107, respectively, each having teeth 108 of special and peculiar shape. These teeth have the shape of arrowheads, and they are arranged with their lateral points so close together that, while a wire or string can pass in between them, it is practically impossible to disengage the same therefrom laterally, and any object to which the string or wire at the inner end may have become attached 35 can not be drawn up between said teeth.

35 The baffle plate 106 has side brackets 109-109 fastened to opposite sides of the receiving hopper 11 in position to locate said plate at a steep incline from the back side of said hopper downwardly and forwardly under the opening at the 40 top of the hopper. The teeth 108 of this plate are at the bottom.

40 To facilitate movement by gravity down the baffle plate 106 of objects (paper tickets more especially), said plate may be provided on the 45 face that receives said objects with longitudinally extending ribs 110. There may be four, more or less, of the ribs 110, and they are preferably struck up out of the sheet metal of which the plate 107 is made.

45 The front side of the baffle hopper 16 inclines downwardly and rearwardly from above, and the baffle plate 107 is set in a slot in the bottom edge of said side, with the teeth 108 of said plate below 50 said edge, and the plate has at each end an ear 115 107' outside of and fastened to the contiguous side of the hopper. The hopper 16 opens underneath the baffle plate 106.

50 A tortuous course for the coins, tokens, or tickets is thus afforded, and the baffle plates 106 120 and 107 are in offset relationship. The objects fall on the plate 106, slide down the same and drop onto the inclined front side of the hopper 16, and slide down said side into the observatory 5 and onto the inspection plates 30, unless said 125 plates be open, in which case the objects pass directly down into the drawer 2.

55 Within the hopper 16 and supported from the back side thereof is a bell 111.

60 Journalized in suitable bearings at the bottom of the receiving hopper 11 is a horizontal rock shaft 112, and journalized in bearing brackets 113-113 that extend downwardly from said hopper into the hopper 16 is a second rock shaft 114. The 65 shafts 112 and 114 are parallel with each other 135 and with the front and back sides of the hoppers 11 and 16. A register 115, of the Veeder type, is fastened to a disc 116 secured to the back side of the hopper 11 over an opening therein, and there is an opening in said disc through which to observe the register numerals. The register 115 has an operating spindle 117 to which is adjustably secured a rock arm 118. Adjustably secured to the shaft 112 is a rocker arm 119, and a link 120 pivotally connects the free terminal of said arm 140 145 with the free terminal of the arm 118.

65 A block 121 is also adjustably secured to the shaft 112. A pawl 122 is pivotally connected at 123 with the blocks 121, but located in a slot in the lower end of said block, and normally held 150

with its lower operating end down in the path of a member (presently to be described) by means of a spring 124, the movement of said pawl under the influence of said spring being limited by the 5 top of said slot. In Fig. 6 the top of the aforesaid slot is indicated by broken lines at 125. The upper end of the spring 124 is fastened to a pin 126 on the back side of the arm 121 near the top, and the lower end of said spring is fastened to the 10 tail of the pawl 122. The member with which the pawl 122 cooperates is a hub 127 mounted on and secured to the shaft 114, and having a tooth 128 which said pawl is adapted to engage and release. A resilient arm 129 has one terminal secured to the hub 127, and is provided at that 15 terminal with a hammer 130 for the bell 111.

The spring 131 is fastened at the upper end to a pin 132 that projects from the front side of the block 121 near the top, and the other end is fastened to a pin 133 that projects from the front 20 of the hub 127.

A stop arm 134 is rigidly attached to the shaft 114 and extends rearwardly over a flange 135 that forms part of the hopper base 17. The shaft 25 112 projects beyond its left-hand bearing and secured to this protruding part is an operating lever 136. The lever 136 extends in a generally forwardly direction, and the movements of the same are limited by a lug 137 that projects from the 30 left-hand side of the base 17 behind said lever when in depressed and normal position, and a lug 138 that projects from the same side of said base above said lever to limit the upward movement of the same.

35 The spring 131 tends to rock the shaft 112 to the right and the shaft 114 to the left. The stop arm 134 while bearing at the rear end on the flange 135 limits the movement imparted by the spring 131 to the shaft 114, and the stop 137 and the lever 136 limit the movement imparted by 40 said spring to the shaft 112. The parts and members as thus disposed are in normal positions, with the tooth 128 in the path of the pawl 122.

When the lever 136 is swung upwardly against 45 the stop 138, the following operations take place resulting in advancing the register 115 one number and causing the bell 111 to sound, the advancing of the register number preceding the sounding of the bell.

50 As the lever 136 is swung upwardly the shaft 112 is rocked in the direction to carry the upper part of the block 121 rearwardly and with it the link 120, and said link imparts a rearward movement to the arm 118 sufficient in extent to cause 55 the spindle 117 to operate the register 115 and present to view through the opening in the disc 116 the next higher number. At the same time the pawl 122 is carried forward by the block 121, engages the tooth 128, and rocks the shaft 114 60 in the direction to raise the arm 134 from the flange 135 and carry the hammer 130 still farther away from the bell 111, it being understood that said hammer is always out of contact with said bell except at the instant of striking. As 65 the block 121 and the hub 127 are thus rocked in opposite directions, the pins 132 and 133 are more widely separated and the spring 131 is placed under greater tension. Finally, after the register has been operated in the manner just 70 explained, the pawl 122 passes clear of the tooth 128 and the spring 131 acts to rock the hub 127 quite violently in the opposite direction, whereby the resilient arm 129 causes the hammer 130 to strike the bell 111. The movement of the striking parts is limited by the arm 134 which comes 75

down onto the flange 135. The vibration afforded by the arm 129 is directly responsible for the blow which the hammer strikes on the bell, because said arm when at rest supports the hammer a little distant from the bell, as previously observed. 80

Upon the release of the lever 136 the spring 131 rocks the block 121 forwardly again at the upper end and rearwardly at the lower end, the link 120 is drawn forwardly and with it the arm 118, thus disposing the register mechanism in readiness for the presentation of the next higher number, the pawl 122 moves back, clicking past the tooth 128 under the influence of the spring 124, into position to reengage said tooth operatively, and said lever is swung downwardly and rearwardly against the stop 137 ready to be moved and impart the next succeeding pulsations to the register and bell hammer. 85 90

The lever 136 should be manipulated to operate 95 the register and sound the bell each time a fare is deposited in the receiving hopper 11.

For the purpose of making known any attempt to invert the fare box in an effort to shake out through the top the objects on the inspection plates 30, a tell-tale 139 and a support 140 are provided. The support 140 consists of a horizontal eye or ring having a shank set in the front of the baffle hopper 16 a short distance above the lower end and in the transverse center thereof. 100 The tell-tale is adapted to rest on the support or ring 140, and has a tail-piece 141 that extends down through said ring when said tell-tale is in position. On top of the tell-tale is a small, undercut head 142. Set in the front of the hopper 110 16 directly above the center of the ring 140 is a stop pin 143.

The fare box is jolted up and down more or less, at which times the tell-tale 139 is projected upwardly and would be liable to leave the ring 115 140 altogether were it not for the pin 143. In rising the tell-tale strikes against the lower end of the pin 143, before the tail-piece 141 leaves the ring, and is thereby caused to drop down onto said ring again. If the tell-tale were to 120 fall completely out of the ring 140 at such times, its usefulness as a detector would be destroyed. In the event the box be tipped to an extent sufficient to enable objects to be shaken out through the entrance to the reservoir hopper 11, the tell-tale falls out of the ring, the pin 143 then being 125 unable to prevent complete disengagement, and said tell-tale can not be replaced on said ring while the drawer 2 is in the case 1. Furthermore, the dislodged tell-tale must eventually 130 135 pass down into the drawer, from which it can only be removed after said drawer is withdrawn from the case, and the cover unlocked and taken off.

A replacer for the tell-tale 139, such as the 135 implement illustrated in Figs. 4 and 5, may be furnished. This implement consists of a suitably bent shank 144 having at one end a finger 145 notched at 146 to receive the small neck under the head 142 of the tell-tale. 140

To replace the tell-tale 139 with the replacer, the head 142 is slipped over the finger 145, the inspection plates 30 are opened and held open, the end of the rod 144 which is carrying said tell-tale is passed into the case 2, from which the 145 drawer has been removed, and up into the observatory 5 until the bottom of the tail-piece 141 is above the ring 140, and said replacer is lowered to drop said tail-piece down through and said tell-tale onto said ring. When the tell-tale 150

becomes engaged with the ring the finger 145 is slipped from beneath the head 142 and withdrawn with the rod 144 from the box.

It is now clear that at practically all points 5 attempts to interfere with the regular and proper functioning of the fare box and operation of its movable parts and members will either fail or be discovered.

The manner in which the fare box is used and 10 the complete operation of the movable parts of said box have already been so fully described that further explanation is deemed to be unnecessary.

I claim:

1. The combination, in a fare box, with a case, 15 a discharge hopper in said case, means to open and close the entrance to said hopper, a drawer receivable in said case, a cover for said drawer, said cover having an opening therein, beneath said hopper, and being provided with a lock 20 block, and a sliding shutter in said cover adapted to open and close said opening, and having a projection at the rear end, of latch mechanism carried by said shutter and adapted to be engaged with and be released from said cover, a 25 lever to actuate said opening and closing means for said hopper, a member normally located in the path of said block, and a member operable therewith normally located out of the path of said projection but movable into said path, a 30 member controlling said first- and second-named members and itself controlled by the position of said lever, whereby said first- and second-named members are retained in normal position by said lever when the latter is in normal position and 35 said opening and closing means is in closed position, and to be released by said lever when operated to open said means, and an operating lever for said three members.

2. The combination, in a fare box, with a case, 40 a discharge hopper in said case, means to open and close the entrance to said hopper, a drawer receivable in said case, a cover for said drawer, said cover having an opening therein beneath said hopper, and being provided with a lock block, 45 and a sliding shutter in said cover adapted to open and close said opening, and having a projection at the rear end, of latch mechanism carried by said shutter and adapted to be engaged with and be released from said cover, a lever to actuate 50 said opening and closing means for said hopper, a member normally located in the path of said block, and a member operable therewith and normally located out of the path of said projection but movable into said path, a member controlling 55 said first- and second-named members and itself controlled by the position of said lever, whereby said first- and second-named members are retained in normal position by said lever when the latter is in normal position and said opening and 60 closing means is in closed position, and to be released by said lever and engage and lock the same when operated to open said means, and an operating lever for said three members.

3. The combination, in a fare box, with a case, 65 a delivery hopper in said case, opening and closing means for said hopper, said means consisting in part of a notched operating lever, yielding means normally to retain said first-named means in closed position, a shaft journaled in said case and provided with arms and with an operating lever, of a drawer receivable in said case, a cover for said drawer having an opening therein beneath said hopper, and provided with a lock 70 block, a sliding shutter in said cover, and provided with latch mechanism to be engaged with

and released from said cover, and having a projecting member at the rear end, yielding means normally to retain one of said arms in the path of said block, another of said arms out of the path of said projecting member, said first-named lever when in normal position being in the path of the third arm, but when out of such position receiving said third arm in the notch in said first-named lever, when said second-named lever can be actuated to remove said first arm from the path of said block and move said second arm into the path of said projecting member.

4. The combination, in a fare box, with a case, a delivery hopper in said case, opening and closing means for said hopper, said means consisting in part of a notched operating lever, yielding means normally to retain said first-named means in closed position, a shaft journaled in said case and provided with arms and with an operating lever, of a drawer receivable in said case, a cover for said drawer having an opening therein beneath said hopper, and provided with a lock block, a sliding shutter in said cover, and provided with latch mechanism to be engaged with and released from said cover, and having an engaging member at the rear end, yielding means normally to retain one of said arms in the path of said block and another of said arms out of the path of said projecting member, said first-named lever when in normal position being in the path of the third arm, but when out of such position receiving said third arm in the notch in said first-named lever, when said second-named lever can be swung to remove said first arm from the path of said block and move said second arm into the path of said projecting member, and itself to be locked until said second-named lever is released to its yielding means.

5. The combination in a fare box, with an inspection-plate opening and closing lever having 115 a notch therein, of a drawer-locking and releasing member, and a member rigidly connected with said first-named member, and adapted to be retained in one position by an unnotched part of said lever, and permitted to move into another 120 position when said lever is moved to locate said notch in position to receive said second-named member.

6. The combination, in a fare box, with an inspection-plate opening and closing lever having 125 a notch therein, of a drawer-locking and releasing member, and a member rigidly connected with said first-named member, and adapted to be retained in one position by an unnotched part of said lever, and permitted to move into another 130 position when said lever is moved to locate said notch in position to receive said second-named member, said notch and said second-named member being so relatively shaped and arranged that said lever is locked while said first-named member is in said notch.

7. The combination, with a fare-box drawer, and a cover for said drawer, said cover having an opening therein, and being provided with a serrated part, of a shutter slidably arranged in 140 said cover to open and close said opening, a spring-pressed latch carried by said shutter in position to engage the serrated portion of said part and lock said shutter to said cover against movement in one direction when said latch is 145 in engagement with any of said serrations and a spring connected to said cover and shutter tending to urge said shutter in an opposite direction.

8. The combination, in a fare box, with a case, a funnel-shaped member mounted on said case 150

and extending into the same, a discharge hopper mounted in said case below said member, the latter on two sides projecting inwardly over contiguous edges of said hopper, shafts journaled in said hopper, and inspection plates rigidly connected with said shafts in position to be limited in their upward movement by said projecting parts, of yielding means normally to retain said plates in contact with said projecting parts, when the plates are in closed position, and means to actuate said shafts in the directions to swing said plates downwardly into open position.

9. The combination, in a fare box, of a case, a discharge hopper in said case, shafts journaled in said hopper, inspection plates mounted on and secured to said shafts, means to limit the upward movement of said plates when they assume a horizontal position, an operating lever mounted on and secured to one of said shafts, an arm mounted on and secured to the other of said shafts, an intermediately arranged lever, a link connecting said first- and second-named levers, a link connecting said arm and said second-named lever, and a spring arranged to act on said levers, arm, and links to actuate them in the direction to close said plates and normally to retain them in closed position.

10. The combination, in a fare box, with a case, a discharge hopper in said case, inspection plates arranged to open and close said hopper, and operating mechanism for said plates, said mechanism being spring pressed to retain said plates normally in closed position, and consisting in part of a lever having a notch therein, of drawer-locking and releasing mechanism comprising a shaft journaled in said case, a lock arm secured to said shaft and having a part in the path of which is said lever when normally disposed, but said part being receivable in said notch when said lever is abnormally disposed, a stop projecting from said case into the path of said arm to check the same when moved into locking position, and a spring arranged normally to retain said arm against said stop.

11. The combination, in a fare box, with a case, a discharge hopper in said case, inspection plates arranged to open and close said hopper, and operating mechanism for said plates, said mechanism being spring pressed to retain said plates normally in closed position, and consisting in part of a lever having a notch therein, of drawer-locking and releasing mechanism comprising a shaft journaled in said case, a lock arm secured to said shaft and having a part in the path of which is said lever when normally disposed, but said part being receivable in said notch when said lever is abnormally disposed, a stop projecting from said case into the path of said arm to check the same when moved into locking position, and a spring arranged normally to retain said arm against said stop, the shape and arrangement of said part and said notch being such that, when said part is in said notch, said lever is held against the action of its spring.

12. The combination in a fare box of a case, a drawer receivable therein below a hopper in said case, a cover, a shutter movable in said cover, the said cover and shutter being provided with openings therethrough, a pair of shafts rotatable in said casing carrying a pair of inspection plates, an operating lever on one of said shafts and connections between said shafts, another shaft rotatable in said case, arms on said shaft for lying in front of parts on said cover and shutter alternately accordingly as the said

shaft is rotated in one direction or the other, a lever on said last-named shaft for manual engagement whereby said shaft may be moved independently of the others and engageable parts associated with the first-named lever and one of the arms on the last-named shaft whereby the operation of the latter is controlled by the other. 80

13. The combination in a fare box of, a case having a drawer slidable therein and a hopper thereabove, a cover for said drawer provided with a shutter, a pair of shafts rotatable in said case at opposite sides of the hopper carrying inspection plates, an operating lever for one of said shafts and connections between said shafts, a spring acting on said connections to yieldingly hold said lever in normal position wherein the plates are in inspection position, a third shaft journaled in said case, separate arms on said shaft angularly disposed for alternately lying in front of parts on said cover and shutter accordingly as the shaft is oscillated between certain positions, a lever for oscillating said last named shaft independently of said pair of shafts, engageable parts associated with said first-named lever and one of said arms to permit movements of said third shaft only when said first named lever is moved away from its normal position. 90

14. The combination in a fare box of, a case having a drawer slidable therein and a hopper thereabove, a cover for said drawer provided with a shutter, a pair of shafts rotatable in said case at opposite sides of the hopper carrying inspection plates, an operating lever for one of said shafts and connections between said shafts, a spring acting on said connections to yieldingly hold said lever in normal position wherein the plates are in inspection position, a third shaft journaled in said case, separate arms on said shaft angularly disposed for alternately lying in front of parts on said cover and shutter accordingly as the shaft is oscillated between certain positions, a lever for oscillating said last-named shaft independently of said pair of shafts, engageable parts associated with said first-named lever and one of said arms to permit movements of said third shaft only when said first named lever is moved away from its normal position. 105

15. The combination in a fare box of a case having an opening in a forward wall thereof, a drawer receivable therein, a forward wall of said drawer adjacent its upper side being provided with spaced openings therethrough and a cover for said drawer having parts receivable in said openings when in place on said drawer whereby said parts are visible when the drawer is inserted in said opening to indicate that said cover is in place on said drawer. 130

16. The combination in a fare box of a case having an opening in a forward wall thereof, a drawer receivable therein, a forward wall of said drawer adjacent its upper side being provided with an opening therethrough and a cover for said drawer having a part receivable in said opening when in place on said drawer whereby said part is visible when the drawer is inserted in said opening to indicate that said cover is in place on said drawer. 140

SAMUEL J. BELL.
